UNITED STATES PATENT OFFICE.

GEORGE E. DEAN, OF ALBION, MICHIGAN, ASSIGNOR TO THE UNION STEEL SCREEN COMPANY, LTD., OF ALBION, MICHIGAN.

BACK.

1,104,970.

Specification of Letters Patent.

Patented July 28, 1914.

Application filed February 8, 1912. Serial No. 676,354.

To all whom it may concern:

Be it known that I, GEORGE E. DEAN, a citizen of the United States, residing at Albion, county of Calhoun, and State of Michigan, have invented certain new and useful improvements in Racks, of which the following is a specification.

This invention relates to improvements in racks.

10 My improved rack is especially designed by me for bakers' use although it is adapted for general use.

15 The main objects of this invention are, first, to provide an improved rack which is easily kept clean and sanitary. Second, to provide an improved rack which is very light in weight and at the same time strong and durable. Third, to provide an improved rack which is very simple and economical in 20 structure.

Further objects, and objects relating to structural details, will definitely appear from the detailed description to follow.

25 I accomplish the objects of my invention by the devices and means described in the following specification.

The invention is clearly defined and pointed out in the claims.

30 A structure which is a preferred embodiment of my invention is clearly illustrated in the accompanying drawing, forming a part of this specification, in which:

Figure I is a perspective view of my improved rack. Fig. II is an enlarged detail 35 perspective showing the manner of securing the supporting or shelf arms to the uprights. Fig. III is a detail vertical section taken on a line corresponding to line 3—3 of Fig. II. Fig. IV is a detail vertical section taken on a line corresponding to line 4—4 of Fig. V of a modified construction, the modification being in the supporting 40 arms and clamping bolt therefor. Fig. V is a detail vertical section taken on a line 45 corresponding to line 5—5 of Fig. IV. Fig. VI is a detail perspective view of a further modification, the modification being in the means for clamping or securing the supporting 50 or shelf arms to the uprights. Fig. VII is a detail horizontal section taken on a line corresponding to line 7—7 of Fig. VI, the supporting arms being shown in full lines.

In the drawing, similar reference characters refer to similar parts throughout the

several views, and the sectional views are 55 taken looking in the direction of the little arrows at the ends of the section lines.

Referring to the drawing, the base 1 is preferably an open rectangular frame having casters 2 at each corner. The uprights 3 are mounted centrally of the end pieces of the base and supported by suitable braces 4. The uprights are formed of angle iron, preferably channel-shaped in cross section, and arranged in an opposed relation and 65 with the channels facing inwardly. The arms of the channels are provided with a series of notches 5 adapted to receive the shelf or supporting arms 6. These supporting arms are in the preferred construction, formed of rods, 70 the opposed arms being connected by integrally formed cross pieces 7. The arms are provided with offsets 8 which are arranged between the arms of the angle iron uprights and secured by means of clamping 75 bolts 9. These clamping bolts in the structure shown in Figs. I to III are provided with hooks adapted to engage the offsets as clearly illustrated. This simple securing means secures the supporting arms and prevents their longitudinal movement.

In the modification shown in Figs. IV and V, the arms 10 are formed separately and provided with hook-like offsets 11 at their inner ends. The clamping bolts 12 are 85 provided with washers 13 adapted to engage these offsets.

In the modified construction shown in Figs. VI and VII, a clamping bar 14 common to all of the supporting arms is provided, this clamping bar being clamped into the offsets 15 of the arms 16 by means of bolts 17.

My improved rack can be formed of very light material and at the same time is strong 95 and durable, and as will be obvious, can be easily kept in a sanitary condition on account of its simplicity in structure, so that it is especially adapted for bakers' use, also has a large capacity in proportion to its 100 size.

I have illustrated and described several modifications so that the application of my invention will be fully understood.

Having thus described my invention, 105 what I claim is new and desire to secure by Letters Patent is:

1. In a rack, the combination with the

base, of channeled uprights arranged oppositely and facing inwardly, the arms of the channels having a series of opposed notches therein, supports comprising rectangular frames of wire arranged between said uprights with their side members engaging opposed notches thereof, the side members of said supports having offsets disposed in the channels of the uprights, and hooked bolts 10 passing through said uprights engaging said offsets, all coacting for the purpose specified.

2. In a rack, the combination with the base, of channeled uprights arranged oppositely and facing inwardly, the arms of the channels having a series of opposed notches therein, endless wire supports arranged between said uprights with their side members engaging the notches thereof, the side members of said supports having offsets disposed 15 in the channels of the uprights, and means for securing said supports to said uprights engaging said offsets within the channels 20

of said uprights, all coacting for the purpose specified.

3. In a rack, the combination with a base, 25 of channeled uprights arranged oppositely and facing inwardly, the arms of said channels having a series of opposed notches therein; rod-like supporting arms arranged in said notches; offsets in said arms disposed in the channels of the uprights; and hook-shaped bolts passing through said uprights and engaging the offsets of said supporting arms whereby the arms are immovably secured to the upright, all coacting for the 30 purpose specified.

In witness whereof, I have hereunto set my hand and seal in the presence of two witnesses.

GEORGE E. DEAN. [L.S.]
